ENGINE DEPOSIT REMOVAL

Paul E. Oberdorfer, Jr., Claymont, Del., assignor to Sun Oil Company, Philadelphia, Pa., a corporation of New Jersey

No Drawing. Application November 15, 1956
Serial No. 622,256

4 Claims. (Cl. 252—143)

This invention relates to a process for removing deposits from the combustion chambers of internal combustion engines, and to compositions of matter suitable for use in such a process.

It is well known to the art that during the operation of an initially clean internal combustion engine, deposits form and accumulate on surfaces within and adjacent to the combustion zone, such as on the cylinder head, spark plugs, piston tops, and valves. These deposits have a number of adverse effects on engine operation, for example, they cause an increase in the octane requirement of the engine, and also contribute to preignition with consequent roughness of operation. The problem of engine deposits is particularly acute when tetraethyl lead is contained in the fuel, since the deposits in this case contain an appreciable amount of lead compounds which adhere firmly to the surfaces on which they are deposited, and which contribute to shorting of the spark plugs, with consequent loss of power.

It is an object of this invention to provide a series of solvent formulations which are highly effective, when brought into contact with engine deposits containing lead, to soften and loosen the deposits to a degree such that, on starting the engine after such contacting, the deposits will break off the surfaces to which they are attached and will be blown out the exhaust, leaving the surfaces in the combustion zone essentially free of deposits.

In my application, United States Serial No. 595,055, filed July 2, 1956, of which the present application is a continuation-in-part, I disclosed that cyclic carbonate inner esters having the formula:

were effective in removing engine deposits. In that application, I disclosed a preferred solvent formulation comprising propylene carbonate, ethyl acetate, and ethylene glycol monoethyl ether. This solvent is highly effective in removing gummy deposits from relatively cool surfaces, such as surfaces of a carburetor, and is also effective to a degree in removing deposits from surfaces in the combustion zone of an engine.

I have now found that if aqueous acetic acid is included as a component of the solvent formulation, superior results may be obtained in removing deposits from the combustion chambers of internal combustion engines which have been operated with a leaded gasoline. The reason why the acetic acid contributes to the effectiveness of the solvent formulation is not definitely known, but it may be that it converts the lead compounds in the deposits to soluble lead acetates, which dissolve during the power stroke of the piston, so that they no longer stick tenaciously to the surfaces to which they are attached, and may be easily removed in conjunction with the carbon deposits loosened by the carbonate inner ester component of the solvent.

2

The preferred compositions of the present invention comprise from about 10% to about 70% of a cyclic carbonate inner ester, from about 10% to about 30% of a low-boiling polar solvent such as acetone, dimethyl acetal, methylal, methanol, methyl ethyl ketone, ethanol, isopropanol, ethyl acetate, and the like, and from about 20% to about 60% aqueous acetic acid, which may range in strength from about 25% to about 75%. Alternatively, a compound which yields acetic acid when exposed to the conditions obtained in the cylinders of an engine under operation, such as aceto-acetic ester, benzal diacetate, acetone diacetate, etc., may be used in place of the acetic acid. The cyclic carbonate inner ester has the formula:

in which R may be hydrogen or a hydrocarbon radical. Typical of such esters are ethylene carbonate:

25 propylene carbonate:

30 butylene carbonates:

35 amylene carbonate:

and its isomers

40 and higher homologues of the above compounds. While in the compounds specifically shown above the hydrocarbon substituents are alkyl, they may also be aryl, alkenyl, or alkaryl, for example, suitable compounds would include phenylethylene carbonate, methyl phenyl ethylene carbonate, or vinyl ethylene carbonate. I prefer to use carbonates which have a boiling point sufficiently high that they do not immediately vaporize upon introduction into the cylinders of an idling engine, since in order to make effective contact with the engine deposits, 45 it is necessary that the carbonate be introduced into the cylinder as a mist which condenses on the surfaces to be treated as a liquid film, in order to effect proper penetration of the deposits. I prefer to use propylene carbonate or higher molecular weight carbonates. If, however, the carbonate is of very high molecular weight, since its solvent power depends on the cyclic ester group, it is obvious that much larger quantities must be used in order to introduce into the engine the same number of cyclic ester groups as when using lower molecular weight esters. For 50 this reason, I prefer that there be not more than about six to nine carbon atoms in the substituent hydrocarbon groups, although for special applications, such as when lubricity in the cleaning composition is desired, higher molecular weight esters may be used. The low-boiling polar solvent component of my new compositions is used chiefly to control their viscosity, but it is thought that it

may also help in removing deposit due to the thermal shock induced by their rapid evaporation upon contact with hot deposits.

Typical solvent formulations according to the present invention are listed below. The invention should not be construed as being limited to these particular formulations, however, since others within the ranges of components given above are also useful.

FORMULA I

	Percent	5
Propylene carbonate	25	10
Acetone	25	
50% acetic acid	50	

FORMULA II

	Percent	15
Butylene carbonates	40	
Methyl ethyl ketone	30	
75% acetic acid	30	

FORMULA III

	Percent	20
Amylene carbonate	50	
Methanol	15	
60% acetic acid	35	

FORMULA IV

	Percent	25
Propylene carbonate	25	
Acetone	25	
Acetoacetic ester	25	
Water	25	

In order to illustrate the effectiveness of my new compositions in cleaning deposits from the cylinders of internal combustion engines, the following examples are given:

Example I

A freshly cleaned 1956 Oldsmobile engine was tested at 2000 r.p.m. and was found to have a power output of 102.1 H.P. and an octane requirement of 87. The engine was run for 120 hours on a leaded gasoline. On retesting it was found that the power output had dropped to 80.3, and the octane requirement had increased to 95. The spark plugs were then removed and replaced with new plugs, and the engine was retested. It was found that the power output increased to 100.1, but the octane requirement remained fairly constant at 93. This indicated that spark plug fouling had been the cause of the loss of power, but other deposits in the cylinders were responsible for the increase in octane requirement. The new plugs were then taken out and the old dirty ones replaced without cleaning.

The engine was then restarted, brought to full operating temperature and throttled to a fast idling speed. The air cleaner was then removed, and about one and one-quarter pints of Formulation I were dripped into the carburetor air intake at the maximum rate which would just prevent engine stalling. A final quarter pint was then added as a slug to stall the engine. Following a soaking period of about one hour, the engine was restarted and was run for about 20 minutes to blow out loosened deposits. It was then retested and found to have a power output of 97.8 H.P. and an octane requirement of 88, which was virtually the same as that of the engine when freshly cleaned. The engine was then taken apart and visually inspected. The surfaces in the combustion zones were found to be essentially free of deposits.

Example II

The same procedure as in Example I was followed in cleaning out a number of late model cars which had accumulated engine deposits in normal driving use. Sig-

nificant reduction in octane requirement was obtained in all cases, as indicated in the following table.

5	Car	Octane Number Requirement	
		Before Cleaning	After Cleaning
10	1956 Ford Fairlane	90	84.5
	1955 Buick Super	96.4	94
	1956 Mercury	96.4	93.5
	1954 Oldsmobile 88	93.2	90.6
	1954 Oldsmobile 98	93.8	89.6

I claim:

1. The method of removing deposits from an internal combustion engine which comprises contacting the deposits with a composition comprising from about 10 to about 70 volume percent of a cyclic carbonate inner ester selected from the group consisting of ethylene carbonate, propylene carbonate, butylene carbonate, and amylen carbonate, from about 10 to about 30 volume percent of an organic polar solvent selected from the group consisting of acetone, dimethyl acetal, methylal, methanol, methyl ethyl ketone, ethanol and isopropanol, and mixtures thereof, and from about 20 to about 60 volume percent of an aqueous solution of a compound selected from the group consisting of acetic acid and compounds capable of yielding acetic acid by thermal decomposition.
- 15 2. The method according to claim 1 in which the composition comprises about 25 volumes of propylene carbonate, about 25 volumes of acetone, and about 50 volumes of fifty percent aqueous acetic acid solution.
- 20 3. A solvent formulation for the removal of engine deposits which comprises from about 10 to about 70 volume percent of a cyclic carbonate inner ester selected from the group consisting of ethylene carbonate, propylene carbonate, butylene carbonate and amylen carbonate, from about 10 to about 30 volume percent of an organic polar solvent selected from the group consisting of acetone, dimethyl acetal, methylal, methanol, methyl ethyl ketone, ethanol, and isopropanol, and mixtures thereof, and from about 20 to about 60 volume percent of an aqueous solution selected from the group consisting of acetic acid and compounds capable of yielding acetic acid by thermal decomposition.
- 25 4. A solvent formulation for the removal of engine deposits which comprises about 25 volumes of propylene carbonate, about 25 volumes of acetone, and about 50 volumes of 50% aqueous acetic acid solution.
